(57) **CLAIM**

We claim the ornamental design for a wireless charger, as shown and described.

DESCRIPTION

FIG. 1 is a front perspective view of a wireless charger showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another right-side view in which the wireless charger is shown in an overlapped position.

The broken lines in the figures depict portions of the wireless charger which form no part of the claimed design.

1 Claim, 5 Drawing Sheets
